UNITED STATES PATENT OFFICE

171,608

COMBINATION ROCKET TOY AND SHAKER CUP

Wilmot Ernest Mather, Ridgewood, N. J.

Application June 12, 1953, Serial No. 25,475

Term of patent 14 years

(Cl. D2—3)

To all whom it may concern:

Be it known that I, Wilmot Ernest Mather, a citizen of the United States, a resident of the village of Ridgewood, county of Bergen, and State of New Jersey, whose post office address is 259 Highwood Avenue in said Ridgewood, New Jersey, have invented a new, original, and ornamental Design for a Combination Rocket Toy and Shaker Cup, of which the following is a specification, reference being had to the accompanying drawing which forms a part hereof.

Figure 1 is a front elevational view of a combination rocket toy and shaker cup showing my new design.

Figure 2 is a top plan view.

Figure 3 is a bottom plan view.

The two sides and rear not shown are substantially the same as the front shown in Figure 1.

I claim:

The ornamental design for a combination rocket toy and shaker cup, substantially as shown and described.

WILMOT ERNEST MATHER.
